UNITED STATES PATENT OFFICE.

GOODWIN B. SMITH, OF PHILADELPHIA, PENNSYLVANIA.

BUST-SUPPORTER.

1,095,681.

Specification of Letters Patent.

Patented May 5, 1914.

Application filed August 5, 1911. Serial No. 642,488.

To all whom it may concern:

Be it known that I, GOODWIN B. SMITH, a citizen of the United States, residing at Philadelphia, in the county of Philadelphia and State of Pennsylvania, have invented 5 certain new and useful Improvements in Bust-Supporters, of which the following is a specification.

This invention relates to a breast reducer 10 and supporter and has particular reference to such a device formed of freely elastic material.

I have found that by making a breast reducer and supporter of elastic material or 15 webbing and weaving the webbing to provide pockets for receiving and conforming to the curvature of the breast, the breast is supported in a natural position and the wearer is not inconvenienced. I wish it to 20 be understood that where I herein employ the term elastic webbing, such term is used in its ordinary acceptance as indicating a fabric having threads or strands of rubber woven therein, so that the strip or section 25 of fabric is capable of freely yielding or stretching longitudinally. The breast reducer being formed of elastic webbing, it exerts a constant and even pressure upon the breast to reduce the same and hold it in 30 a natural elevated position. The breast supporter being formed of elastic webbing will yield and give when the wearer moves, thus rendering its use easy and comfortable.

The device is so constructed that it will 35 not allow the breast to slip and will not itself be liable to displacement. The bulging or concave portions forming pockets to receive the breast are formed by weaving the elastic web in a special manner.

An important object of this invention is 40 to provide a device of the above mentioned character, which is light, comfortable, strong, durable, and cheap to manufacture.

Other objects and advantages of this in- 45 vention will be apparent during the course of the following description.

In the accompanying drawings forming 50 a part of this specification and in which like numerals are employed to designate like parts throughout the same, Figure 1 is a perspective view of the device as a whole, Fig. 2 is a front elevation of the elastic webbing having the breast receiving pockets

formed therein, Fig. 3 is a front elevation of the device flattened, the shoulder strap 55 being omitted, Fig. 4 is an edge view of the same, Fig. 5 is a sectional view on line 5—5 of Fig. 2, and, Fig. 6 is a similar view on line 6—6 of Fig. 2.

My breast reducer and supporter com- 60 prises a front section of freely elastic material 1, preferably of elastic webbing to the ends of which are attached tabs 1' having connection with straps 2, preferably formed of cloth or any suitable flexible and 65 relatively non-extensible material. These straps have their adjacent ends attached to a section of elastic webbing 3, as shown, to allow of the free and easy movement of the body. One of the straps 2 is formed in two 70 sections, which are adjustably connected preferably by glove fasteners, the socket elements 2^a being attached to one section and the ball elements 3^a being attached to the other section, thus providing means to in- 75 crease and decrease the circumferential size of the supporter.

The device is supported upon the wearer by shoulder straps 4, each of which com- 80 prises a front section of tape 5 or other flexible and relatively non-extensible material. The section or tape 5 is detachably connected with the section 1 by a pin 6, or analogous device. The tape 5 has its rear end attached to a section or strip of elastic 85 webbing 7, which is attached to the strap 2 near its front end to allow of the free and easy movement of the arms. The device is prevented from rising up by a strap 8, which is attached to the section 1 midway its ends, 90 as shown, and provided at its lower end with a socket element 9, to engage a steel element (not shown) on the wearer's corset.

The invention particularly resides in the novel formation of the freely elastic front 95 section to provide bulging breast receiving pockets to receive the breast and conform to the curvature of the same. This front section 1 has a reduced or narrow flat intermediate portion 10, which widens at its ends to form outwardly bulging pockets 11, to receive the breast of the wearer. These pockets are curved in cross-section, as shown, to snugly receive and conform to the curvature of the breast. The materials of the pockets 11 become more narrow or taper

toward their outer ends, as shown. Up to very recently it was impossible to weave elastic webbing to form a bulging pocket, as shown in my device. This, however, can now be done. The front section 1 may preferably be woven with selvage edges 11^a, as shown.

Attention is called to the manner in which the front section 1 is woven to produce the flat intermediate portion 10 and the bulging pockets 11. The central elastic warp thread 12 is straight and extends through the longitudinal center of the sections. The upper and lower elastic warp threads 13 are curved longitudinally, being spaced farther apart at the center of the pockets 11 and coming closer together at the ends of the pockets. The warp threads are parallel in the intermediate portion 10, whereby the same is flat and not curved in cross-section as are the pockets.

The numeral 14 designates the woof threads, which are relatively non-extensible.

In order that the longitudinal edges of the front section 1 may not chafe or otherwise inconvenience the wearer, ruffles 15 are attached thereto, which are extensible and formed of suitably soft fabric folded in accordion plaits.

It is thought that a description of the use of the device is unnecessary, the same being obvious.

I wish it understood that the form of my invention herewith shown and described is to be taken as a preferred example of the same and that certain changes in the shape, size, and arrangement of parts may be resorted to without departing from the spirit of the invention or the scope of the subjoined claims.

Having thus described my invention, I claim:

1. A device of the class described comprising a bust-supporting body having a pair of pockets of elastic webbing spaced a substantial distance apart, a relatively flat intermediate section occupying the space between the pockets and connecting the latter, and means for securing the bust-supporting body on the wearer. 45

2. In a device of the class described, an integral bust-supporting section of woven elastic webbing, comprising two relatively wide bulging pockets spaced a substantial distance apart and adapted to snugly receive and conform to the natural curvature of the breasts and a relatively flat spacing section lying between the pockets, and means for securing the bust-supporting section in position on the wearer. 50 55

3. A device of the character described comprising a bust supporting body having a pair of pockets of woven elastic webbing spaced a substantial distance apart, each pocket being wider at its central portion 60 than at its ends, the longitudinal or warp threads of the webbing being elastic and disposed relatively close together near the ends of the pockets and diverging toward the center thereof, a relatively flat intermediate section occupying the space between the pockets and connecting the latter, and means for securing the bust supporting body on the wearer. 65 70

In testimony whereof I affix my signature in presence of two witnesses.

GOODWIN B. SMITH.
